US00D722601S

(12) **United States Design Patent**
Yang

(10) **Patent No.:** **US D722,601 S**
(45) **Date of Patent:** **** Feb. 17, 2015**

(54) **DETACHABLE ASSEMBLY OF MEMORY MODULE**

(71) Applicant: **Adata Technology Co., Ltd.**, New Taipei (TW)

(72) Inventor: **Yujen Yang**, Taipei (TW)

(73) Assignee: **Adata Technology Co., Ltd.**, New Taipei (TW)

(**) Term: **14 Years**

(21) Appl. No.: **29/451,315**

(22) Filed: **Mar. 29, 2013**

(30) **Foreign Application Priority Data**

Jan. 30, 2013 (TW) 102300810

(51) **LOC (10) Cl.** **14-02**

(52) **U.S. Cl.**

USPC **D14/436; D14/438**

(58) **Field of Classification Search**

USPC D14/435–438, 478–480; 235/441, 443, 235/487, 492, 493, 495; 361/679.32, 737, 361/679, 752, 736, 728, 796, 797, 729, 730, 361/725–727; 257/678, 679, 693, E23.064; 439/946, 948, 159; 174/250, 260, 52.1, 174/52.2; 710/300–303; 438/121

See application file for complete search history.

(57) **CLAIM**

The ornamental design for a “detachable assembly of memory module,” as shown and described.

DESCRIPTION

FIG. 1 is a perspective view of a detachable assembly of memory module showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view showing the practical usage thereof.

The broken lines depict portions of the detachable assembly of memory module which form no part of the claimed design.

1 Claim, 6 Drawing Sheets
